Attorney

UNITED STATES PATENT OFFICE

DAVID HENRY OSBORNE, OF JEFFERSONVILLE, PENNSYLVANIA, ASSIGNOR, BY MESNE ASSIGNMENTS, TO ELECTRIC SERVICE SUPPLIES COMPANY, OF PHILADELPHIA, PENNSYLVANIA, A CORPORATION OF PENNSYLVANIA

COUPLING FOR WIRES AND CABLES

Application filed May 23, 1927. Serial No. 193,488.

This invention relates to insulator caps and with regard to certain more specific features, to insulator caps having demountable supporting means.

Among the several objects of the invention may be noted the provision of an insulator cap requiring the minimum of relative movement between the cap and the wire supported, in order to effect a coupling with the supporting pin for the cap; the provision of an insulator cap adapted not to crush the locking key thereof, during ordinary service and which, on the other hand, will not readily uncouple from its pin, although said key be omitted inadvertently; the provision of a device of the class described which will not tend to crush said key; and the provision of a device of the class described which is stronger and more rugged than previously constructed devices of its general class but which costs no more to manufacture. Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claim.

In the accompanying drawings, in which is illustrated one of various possible embodiments of the invention,

Fig. 1 is a plan view of the cap, showing the supporting pin thereof partly broken away;

Fig. 2 is a front elevation of Fig. 1, showing parts in section; and

Fig. 3 is a fragmentary vertical section taken on line 3—3 of Fig. 1.

Corresponding reference characters indicate corresponding parts throughout the several views of the drawings.

The class of cap herein described is of the side-opening type. Various means have been devised for securing to these caps suitable connecting means, adapted to suspend the cap and its insulator from a support, but the means that have hereinbefore been devised are open to the objection that the portion of the cap engaging the connecting means read-

ily gives away under load. Another objection to the former constructions is that the connecting means (a pin) tends to disengage from the cap when a certain key is omitted and when the supported cable or wire suddenly springs or vibrates, as when suddenly relieved of a load of ice, that is, the pin and the cap spring or creep apart.

One of the obvious ways of solving the said problem of spontaneous disengagement is to increase the relative movement required to separate the pin and the cap. However, this solution is open to the objection that an excessive amount of wire slack must be taken up for installation purposes. The present invention prevents the spontaneous disengagement but does not objectionally increase the relative movement required for mounting. Furthermore the cap is increased in mechanical strength.

Referring now more particularly to Fig. 1, there is illustrated at numeral 1 a metallic bell-shaped insulator cap or body portion composed preferably of malleable iron. This cap 1 is adapted to receive within the hollow bell-shape thereof an insulating member or the like (not shown), in most cases composed of porcelain. The insulating member is suitably cemented within the bell-shaped cap 1, the sloping lip 3 of the member 1 serving to key the cement in place after it has dried. The cement is usually a Portland cement.

A supporting pin 5 is coupled to each cap 1 and the manner of coupling comprises the present invention per se. The pin 5 may itself be cemented within the hollow portion of one of the described porcelain insulating members, that is, the lower end of each assembled insulator (comprising a cap 1 and cemented porcelain) may have a non-swiveling pin 5 protruding downwardly therefrom. A series of insulators may be joined together, if desired, or one insulator may be applied to a single pin 5, the latter supported from its upper end in any suitable manner.

Referring again to the drawings, it may be seen that the cap 1 has an enclosing top wall 7 which completes its bell-shape. Formed integrally with the cap 1, above the

wall 7, is a pocket 9, shaped so as to have substantially parallel spaced portions or walls 11, joined at the rear by a curved portion 13. The walls 11 and the portion 13 form a U-shaped projection U (see Fig. 1).

The said U-shaped projection U is provided at its upper periphery with an inwardly turned flange composed of a ring-shaped portion 15, forming a hole 17, and a pair of continuing shelves 19 on the walls 11. The shelves 19 are slightly lower in elevation than the ring-shaped portion 15, although this is not necessary.

Beneath the overhanging shelves 19 of the walls 11 are formed lugs 21. These lugs extend forwardly to the free or open ends of said shelves 19 and walls 11 and are preferably slanted upwardly from said open ends, back toward opening 17 (see Fig. 3).

An opening 23 is provided at the curved portion 13 for the purpose of introducing a spring cotter key 25, as illustrated in the drawings. The purpose of this will appear hereinafter.

The supporting pin 5 is provided with a properly shaped upper end 26 for supporting it. The lower end comprises a mushroom-shaped head 27, above which is located a reduced neck or shank 29, adapted to be movably accommodated in the slot 31 between said shelves 19 and to pass into said opening 17. The head has a diameter less than the distance between the walls 11 but greater than the width of the slot 31 and the opening 17. The underside of the ring-shaped flange 15 is counter-sunk to accommodate an upward movement and a socketing of said head 27 (see Figs. 2 and 3).

The purpose of the lugs 21 is to cause a positive downward movement of the head 27 each time that the pin 5 is applied to or removed from the cap. The distance between the lowermost outer ends of the lugs 21 and the wall 7 is such that the head 27 may pass in and out, if its movement is not interfered with, such as by means of the introduction of said cotter key to said opening 23. When the cotter key 25 is in place, it forms an obstruction to the insertion or removal of the head 27, because it prevents a substantial depression of the head 27. If the cotter key is not in place it is not difficult to depress the head 27 by manual means, thereby making it readily removable.

However, spontaneous separation, under the conditions above described, does not readily take place, first, because of the length of the shelves 19 with their lugs 21, and second, because of the sloping characteristics of said lugs 21. In other words, these features in combination, result in no vibratory movement of the cap 1 being capable of ejecting the head 27 from its recess, even though the key 25 be omitted. Before more than one or, at most, a few vibra-

tory movements can take place the gravitational effect of the load results in a re-socketing of the head 27 in the counter-sunk recess beneath the opening 17.

It is evident that the extensions 11 and shelves 19 materially increase the strength of this cap at the support, that is, the strength is greater than that of those side-opening caps having a mere round conical or like socket at the top. The reason for this is that the extensions 11 and 19 compensate for the loss of strength, due to a side opening. They form a bracing webbing at the same time that they perform their other functions.

The operation of assembly is as follows:

The enlarged, rounded head 27 of the pin 5 is passed between the free ends of the parallel walls 11 and beneath the lower, outer ends of the lugs 21 and slipped beneath said lugs 21 into engagement with the counter-sunk socket of the raised ring-shaped portion 15. It will be noted that the lugs 21 terminate at distances from the flange 15, such that the head 27 is snugly accommodated in its upper position.

Next, the cotter key or pin 25 is passed through the opening 23, whereby it is caused to extend beneath the head 27 to prevent removal of said head.

Should the cotter key inadvertently become displaced, the head 27 will normally be retained in engagement with the flange 15 by the load. Should the supporting wire or cable spring, due to the release of an abnormal load of ice or the like, and cause a jump of the head 27 down beneath the lugs 21, said head will tend to slide back to normal position, because of the slant of the lugs 21.

This cap, being of the side entrance type requires little relative movement for assembly, as is evident from the drawings.

It will be noted from Fig. 3 that the proportions are such as to leave space between the head 27 and the key 25 when the cap is suspended from said head. This means that when relative swiveling actions take place between the cap 1 and the pin 5, during service, then the head 27 will not tend to crush and cut the key 25. This action in former caps has resulted in the loss of the key 25. Then, if the wire had an ice load that suddenly dropped off, causing travel of the wire of an inch or two or more, and some angle swing of the cap or slight travel of the cap with respect to the pin, then the pin would let the cap drop. This action is obviated by means of the present invention, whether the key 25 is in or out of position.

In view of the above, it will be seen that the several objects of the invention are achieved and other advantageous results attained.

As many changes could be made in carrying out the above constructions without departing from the scope of the invention, it is

intended that all matter contained in the above description or shown in the accompanying drawings shall be interpreted as illustrative and not in a limiting sense.

5 I claim:

An insulator cap comprising a body portion, and a pocket portion adapted to receive a pin having a shank portion and an enlarged head portion, said pocket portion having a 10 socket therein acting as a seat for the head portion of the pin and an aperture through which the shank portion of the pin extends when the head is seated in the socket, and being provided with a side opening through 15 which the pin is movable into the socket, said opening consisting of a lower enlarged passageway for the passage of the head portion of the pin and an upper restricted passageway for the passage of the shank portion of 20 the pin but too small for the passage of the head portion, the walls of said restricted passageway extending below the level of the socket whereby the head in movement towards or from the socket must be depressed 25 below the socket level, the upper walls of the enlarged passageway being inclined upwardly towards the socket whereby a vertical force on a pin having its head in said enlarged passageway tends to move the head 30 inwardly into the socket.

In testimony whereof, I have signed my name to this specification this 16th day of May, 1927.

DAVID HENRY OSBORNE.
